SMALL PARTS RECEPTACLE AND DISPENSER

Charles W. Doepeke and Otmar L. Moehringer, Cincinnati, Ohio, assignors to The Charles Wm. Doepeke Manufacturing Company, Cincinnati, Ohio, a corporation of Ohio

Application March 2, 1954, Serial No. 413,583

9 Claims. (Cl. 222—165)

This invention relates to a receptacle for storing and handling small parts such as bolts, nuts, washers and the like, and is particularly concerned with a structure adapted to receive the parts in their original container such as a box or keg and by a simple manipulation to eject the parts from the container and dispose them in a ready position for use.

In many factory operations, particularly in assembling, where a number of adjacent workmen are performing the same or similar operations, it is highly desirable that a regular supply of the various parts involved in the assembling be maintained in a position convenient to the workers. It is also desirable that the parts be so disposed that a number of workers can utilize the same source of supply and that this be done with a minimum of effort and inconvenience to one another.

In a typical factory assembly operation, a group of workers performing the same step or successive steps which require utilization of the same parts conventionally will work side by side along a bench or a series of benches. If the step or operation is to be performed on the bench with the workmen facing it, it is conventional to dispose the parts to the rear of the workmen on tables or benches adapted for this particular purpose. It is also customary, in large factories particularly, to provide employees charged with the duty of maintaining a regular supply of parts for the assemblers. Usually this is done by simply depositing the original parts containers on the benches or tables at the rear of the workers and replenishing the supply from time to time as replenishment is indicated.

In accordance with this practice, the assemblers are required to dip manually into the container and, particularly if the supply of parts is low, this is an awkward and time consuming operation. Emptying the container on the bench or table is messy, space consuming and equally unsatisfactory. After the supply from the container has been exhausted, there is apt to be a material time lag before the supply is replenished. All of these factors tend to add to the cost of the manufacturing operation.

The basic concept of the present invention has been to create a parts receptacle and dispenser into which the person charged with the duty of maintaining the supply of parts can insert the original container and then quickly and readily manipulate the device to an inverted position to eject the parts from the container into the receptacle to a position where they can be utilized with a maximum of efficiency by one or a plurality of workmen. When the supply has been fully utilized the device can then be returned to its original upright position by the workmen, and such positioning in a row of like devices constitutes a signal to the parts supplying employee that more parts are required at this particular point. In this way there is a minimum of time lag in replenishing the supply for the workmen.

In its inverted dispensing position, the receptacle is poised along a downwardly inclined axis and the parts naturally flow by gravity from the inverted container

2

within it, then downwardly into an open chute at the lower end of the receptacle. The level of the mass of parts in the chute is controlled by a gate extending across the chute; to accommodate the flow characteristics of various kinds of parts, the gate may be adjusted to different elevations in the chute. As the parts are dipped out they are replaced by others which flow outwardly from beneath the gate into the forward portion of the chute, thus keeping the level constant until the supply is exhausted.

In the drawings there is illustrated a preferred embodiment of a device embodying the principles of the invention.

Figure 1 is a side elevation of the receptacle in inclined dispensing position, the upright loading position being indicated in broken lines.

Figure 2 is a front elevational view of the device in the same position.

Figure 3 is a sectional view along the line 3—3, Figure 2.

Figure 4 is a side elevational view of the device in loading position and with the closure plate and gate, which controls the flow of parts, swung to an out of the way position to allow a container of parts to be placed in the receptacle.

Referring again to the drawings for a further and more detailed description of the invention, attention is first directed to Figure 4 which, as previously stated, shows the device in loading position. As shown, the assembly includes the base or support member, indicated generally at 10, having a hopper or receptacle 11 pivotally mounted upon it by the trunnions or pivot pins 12. The pivot pins are mounted on each of the side walls of the receptacle in corresponding positions and project outwardly from the mounting pads 13. The mounting pads are attached to the side walls by the screws 14 and by welding as at 15.

The base 10 is generally U-shaped as viewed from the front (Figure 2) and is fabricated from heavy gauge sheet metal. It comprises a bottom plate 16 pierced with holes for optional permanent fastening to a table and spaced side walls 17 rising vertically from the bottom plate in parallelism with one another. The side edges of the walls converge upwardly toward one another from the bottom plate in triangle fashion and terminate in a flat upper edge 18 which includes an open slot 20. The pivot pins are rotatably journaled in the slots at opposite sides, permitting the receptacle to be pivoted from the upright loading position shown in Figure 4 to the inverted dispensing position shown in Figure 3. The projecting portion of each pivot pin has a groove 21 corresponding in width to the thickness of the side walls 17 of the base to center the receptacle between the side walls.

Positioned on the base plate 16 at the rear thereof and secured to the side walls 17 by welding or the like is a channel member 22. This member extends completely across the base and serves as a support for the bottom of the receptacle when the receptacle is in upright loading position as in Figure 4.

The width of the receptacle, as viewed in Figure 2, is slightly less than the spacing of the side walls 17 of the base such that the clearances, as indicated at 23, are provided between the receptacle and its supporting base. The receptacle is fabricated from sheet metal and is of square, box-like construction having an open face 24 and an inclined dispensing chute 25 at one end.

Described in detail, the receptacle includes a pair of side walls 26, a rear wall 27 and an end wall 28. The side walls include right angular marginal flaps 30 which are secured to the rear wall, preferably by welding. The end portions of the side walls, as viewed in Figure 3, are in-

clined outwardly from the rear toward the open face to provide the angle of the dispensing chute 25. The rear wall 27 is correspondingly bent to provide the chute bottom or flow plate 31. The forward end portion of bottom 31 is bent upwardly to form a generally vertical retainer lip 32.

When the receptacle is in its inverted dispensing position (Figure 3), the parts flow by gravity from the original parts container, such as the keg 33, indicated in broken lines, then down the inclined flow plate 31 toward the open face of the chute. The flowing parts are restrained by the lip 32 such that a mass of parts is confined in the chute to be dipped out by the workmen as needed. The parts naturally assume an angle of repose in the chute at a level determined by the gate 34 which may be adjusted vertically in accordance with the nature of the parts.

The gate extends completely across the open face of the receptacle (Figure 2) with its lower edge portion projecting downwardly into the chute toward the flow plate 31. The lower edge thus defines an outlet opening 35 leading into the open forward portion of chute 25. The upper portion of the gate, or more precisely, its mounting structure as described later, forms a barrier adjacent the open end of the container 25; in other words, the gate structure and adjoining portions of the receptacle form a hopper area 36 immediately below the open end of the container to receive the parts and to feed them forwardly into the open portion of the chute.

Described in detail with reference to Figure 3, the gate 34 is supported by a closure plate 37 which is pivotally connected by the screws 38 to the side walls of the receptacle. As described later in detail, the closure plate, with the gate mounted upon it, may be swung about the pivot screws outwardly as shown in Figure 4, to allow the container to be placed in the upright receptacle. In the inverted position of the receptacle shown in Figure 3, the angular pivoted portion 40 of the mounting plate lies in a generally perpendicular plane and the swinging portion 41 resides flush with the open face of the receptacle. It will also be noted that the pivoted plate portion 40 resides in a plane substantially at right angles to the chute bottom or flow plate 31. The closure plate is provided with flanges 42 along its opposite side edges which nest between the side walls 26 of the receptacle. The pivot screws 38 pass through the flanges 42 and walls at opposite sides and include nuts 43 at the external surface of the receptacle.

Referring to Figure 3, the gate 34 is mounted upon the angular portion 40 of the closure plate at right angles to the chute bottom 31 for vertical adjustment by loosening the wing nuts 44 which are threaded upon the screws 45. The screws project forwardly from the closure plate and have heads 46 welded to the plate. The threaded portions of the screws project outwardly through slots 47 formed in the gate (Figure 2). Upon loosening the wing nuts, the gate may be raised or lowered by grasping the handle 48 which is welded to the external surface of the gate. This adjusts the size of the outlet opening 35 as required by the size of the parts or other factors. For stiffening purposes, the side edges of the gate are provided with the angular flanges 50.

In its closed position, the closure plate 37 is locked by a pair of swinging latches 51 which are pivotally mounted as at 52 upon the side walls of the receptacle. A standard tension spring (not shown) is placed on the pivot pins 52 between the latches and wall to hold the latches by friction in any desired position. The swinging end of each latch is provided with a slot 53 which engages respective latch pins 54 mounted upon the flanges 42 of the closure plate. In order to provide clearance for the latch pins 54, the side edges of the receptacle walls include generally V-shaped open slots 55 which are shaped in accordance with the arcuate path described by the pin as the cover plate is swung to its open position about pivot screws 38. Each latch 51 is provided with a flange 56 along its upper edge, providing a hand grip for manipulating the

latch. When in closed position (Figure 1), the engagement of the latch pins 54 in notches 55 limits the inward position of the closure plate.

The latch structure is in duplicate at opposite sides of the receptacle and the latched closure plate engages the periphery of the keg 33 to confine it in the receptacle. The rearward portion of the keg is cradled about three sides within the side and rear walls of the receptacle. In its inverted position shown in Figure 3, the lower end of the keg rests against the inclined pivoted portion 40 of the closure plate to restrict the keg against motion along its inclined axis.

When the receptacle is pivoted to its upright position for loading as shown in Figure 4, the end wall 28, which now forms the bottom of the receptacle, rests upon the transverse channel 22 of the base. This supports the receptacle in stabilized condition to receive the keg or other parts container. The dispenser is preferably mounted upon a worktable, as indicated earlier, in order to supply the parts at a convenient elevation to the workmen. In the upright position, the bottom 28 is disposed in a plane slightly elevated above the supporting surface for conveniently inserting the container.

Before the parts container is placed in the upright 25 hopper, the latches 51 are swung to a disengaged position and the closure plate is swung upwardly about its pivotal axis to the open position shown in Figure 4. It is latched in this position by either of two retainer arms 61 which are pivotally mounted at each side of the receptacle. The 30 pivoted end of each arm is connected to the receptacle by the pivot screw 62 which includes a nut 63 externally of the receptacle. The outer or swinging end of each retainer arm includes a notch 64 which engages the latch pin 54 to lock the cover plate in elevated position. In 35 this position a container of parts can readily be placed in the receptacle from the side. The pivot screw 62 of the retainer arm is spaced upwardly from the pivot screw 38 of the closure plate, such that the arm and closure plate are angularly related when in latched position, with 40 the load carried in tension by the arm. After the container is placed in the receptacle, the retainer arm is released and the closure plate is swung to closed position, then latched as shown in Figure 1.

In upright position, the receptacle is slightly overbalanced to the left, as viewed in Figure 4, the location 45 of pivot bearings 12 being slightly off center to the right for this purpose. The outwardly projecting closure plate assembly increases the overbalance. The receptacle is stabilized in this position by engagement of its bottom against the transverse channel 22. After the closure plate is closed and latched, the receptacle, with the parts container in it, is rotated about its trunnion bearings toward the right as indicated by the arrow in Figure 4. The pivot bearings are located somewhat above the center of gravity of the upright receptacle and, as noted above, 50 off center to the right as viewed in Figure 4. When loaded, the receptacle is poised nearly in balance with its contents forming a partial ballast tending to stabilize it in upright position; therefore, even with a heavy load, the receptacle can be pivoted towards its inverted position without excessive effort. As the inclination of the 55 axis of the receptacle and container increases, but before reaching the full inverted position, the container will slide downwardly to the position shown in Figure 3; thereafter, the parts within it will flow into the hopper 60 36 and through the opening 35 into the open forward portion of the chute.

It will be noted in Figure 3, that the shifting of the 65 container and parts toward the chute will cause the center of gravity of the receptacle to shift to some point below the axis of the trunnion bearings. Therefore, when inverted, the receptacle is overbalanced and is stabilized in this position by the engagement of the forward position of the chute upon the supporting surface as indicated at 65 in broken lines. It will be understood

that, in its inverted position, the major weight load of the receptacle is carried upon the trunnion bearings, while a minor portion of the load overbalances the receptacle in inverted position. The bottom plate of the base has a substantial width and firmly stabilizes the receptacle in its inverted dispensing position.

As the parts are dipped out of the open forward end of the chute, they are replaced by other parts flowing through the opening 35 as explained earlier. The angle of inclination of the receptacle and container causes the parts to flow naturally until the supply is exhausted. At this time the receptacle is pivoted back to its upright position for replacement of the empty container with a filled one.

Having described our invention we claim:

1. A dispensing receptacle arranged to reside in upright position to receive a container of parts and to be inverted for delivery of the parts by gravity to a dispensing position, said dispensing receptacle comprising, a base having a bottom member and a pair of spaced parallel side walls rising upwardly therefrom, a parts receptacle having a rear wall, a pair of side walls extending forwardly from the rear wall, and an end wall, the end portion of the receptacle opposite said end wall forming a dispensing chute having opposite sides delineated by said side walls, said receptacle and chute having an open face delineated by the forward edges of the side walls and end wall, the rear wall having an endwise portion inclined forwardly from the plane of the rear wall toward the open face of the receptacle providing a bottom for the chute, a gate extending transversely across the side walls of the receptacle intermediate the length of the chute in a plane substantially at right angles to the bottom of the chute, the gate having a lower edge spaced outwardly from the chute bottom and delineating an opening, and a pair of pivot pins projecting outwardly from the side walls of the receptacle, the upper ends of the side walls of the base having respective bearings rotatably journaling said pivot pins and cradling the receptacle upon said base for rocking motion selectively to an upright or inverted position, the end wall residing between the side walls of the base in the upright position of the receptacle to support the container, the receptacle and parts container being disposed along a downwardly inclined axis in the inverted position of the receptacle to feed the parts by gravity from the container to the chute.

2. A dispensing receptacle arranged to reside in upright position to receive a container of parts and to be inverted for delivery of the parts by gravity to a dispensing position, said dispensing receptacle comprising, a base having a pair of spaced receptacle support elements rising upwardly therefrom, a parts receptacle having a rear wall and a pair of side walls extending forwardly from the rear wall, the receptacle having an end wall and having an open dispensing portion at its opposite end, the rear wall having an endwise portion inclined forwardly from the plane of the rear wall and providing a bottom for the open dispensing portion, a gate extending transversely across the side walls of the receptacle and delineating the open dispensing portion, said gate disposed in a plane substantially at right angles to the said bottom, the gate having a lower edge spaced outwardly from said bottom and delineating an opening leading to the dispensing portion, a gate mounting structure attached to the receptacle, releasable attachment means on the mounting structure engaging the gate, the gate being shiftable in said plane at right angles to the bottom upon release of the attachment means, and a pair of pivot pins projecting outwardly from the side walls of the receptacle, the support elements of the base rotatably journaling said pivot pins and cradling the receptacle upon the base for rocking motion selectively to an upright or inverted position, the end wall residing between the support elements of the base in the upright position of the receptacle

5 to support the parts container, the receptacle and parts container being disposed along a downwardly inclined axis in the inverted position to feed the parts by gravity to the open dispensing portion.

3. A dispensing receptacle arranged to reside in upright position to receive a container of parts and to be inverted for delivery of the parts by gravity to a dispensing position, said dispensing receptacle comprising, a base having a bottom member resting upon a support surface and a pair of spaced receptacle support elements rising upwardly therefrom, a parts receptacle having a rear wall, a pair of spaced side walls and an end wall, the receptacle having a dispensing chute opposite the end wall, the said rear wall having an endwise portion inclined forwardly from the plane of the rear wall and providing a chute bottom, a gate secured to the receptacle and extending transversely across the chute bottom, the gate having a lower edge spaced outwardly from the chute bottom and delineating an opening, and a pair of pivot pins projecting outwardly from the side walls, said pivot pins being disposed upon a common axis extending transversely of the receptacle and parallel to the rear wall thereof, said axis spaced a lesser distance from the end wall than from the end of the chute, the support elements having bearings rotatably journaling the pivot pins, the bearings spaced above the bottom member of the base a greater distance than the space from the end wall to the axis of the pivot pins, said pivot bearings cradling the receptacle upon the base for rocking motion selectively to upright or inverted position, in upright position the end wall residing in a generally horizontal plane above the bottom member of the base, in inverted position the receptacle being disposed along an inclined axis with the bottom of the chute engaging the support surface adjacent the base.

4. A dispensing receptacle arranged to reside in upright position to receive a container of parts and to be inverted for delivery of the parts by gravity from the container to a dispensing position, said dispensing receptacle comprising, a base having a pair of spaced receptacle support elements rising upwardly therefrom, a parts receptacle having a rear wall, a pair of spaced side walls extending from the rear wall, and an end wall, the end portion of the receptacle opposite said end wall forming a dispensing chute having opposite sides delineated by said side walls, said receptacle and chute having an open face delineated by the forward edges of the side walls and end wall, the rear wall of the receptacle having a portion inclined outwardly toward said open face and forming the bottom of the chute, closure means pivotally connected to the open face of the receptacle and movable to an open position or to a closed position, the closure means extending across the open face to confine the parts container in the receptacle, releasable latch means on the receptacle engaging the closure means in closed position, a gate mounted on the closure means and extending transversely across the dispensing chute and residing in a plane substantially at right angles to the bottom of the chute, when the closure means is in closed position, the gate having an edge spaced outwardly from the bottom of the chute and delineating an opening, and a pair of pivot bearings projecting outwardly from the receptacle at opposite sides, said pivot bearings disposed upon a common axis extending transversely of the receptacle parallel to the rear wall thereof, the support elements of the base rotatably journaling said pivot bearings and cradling the receptacle upon said base for rocking motion selectively to an upright or inverted position, in upright position said end wall being disposed at the lower end of the receptacle to support the container of parts, in inverted position the chute being disposed at the lower end of the receptacle, thereby to feed the parts by gravity from the container to the chute.

5. A dispensing receptacle arranged to reside in upright position to receive a container of parts and to be

inverted for delivery of the parts by gravity to a dispensing position, said dispensing receptacle comprising, a base resting upon a support surface and having a pair of spaced receptacle support elements rising upwardly therefrom, a parts receptacle having a rear wall, a pair of spaced side walls extending from the rear wall, and an end wall, the end portion of the receptacle opposite said end wall forming a chute having opposite sides delineated by said side walls, said receptacle and chute having an open face opposite said rear wall, the rear wall having an endwise portion inclined forwardly from the plane of the rear wall toward the open face providing a bottom for the chute, closure means on the receptacle extending across a portion of the open face to confine the parts container in the receptacle, a pair of pivot bearings projecting outwardly from the receptacle at opposite sides, the support elements of the base rotatably journalling said pivot bearings and cradling the receptacle for rocking motion upon the base respectively to an upright or inverted position, the support elements journalling the pivot bearings at an elevation above the support surface sufficient to provide motion of the receptacle through an arc substantially greater than 90° upon rocking movement thereof from upright to inverted position, thereby to dispose the receptacle and a parts container along a downwardly inclined axis with the chute disposed at the lower end of said axis and resting upon the support surface, said inclined axis causing the parts to flow by gravity from the container through said opening to the chute, whereby the weight load of the parts in its lower portion stabilizes the receptacle in inverted position.

6. A dispensing receptacle arranged to reside in upright position to receive a container of parts and to be inverted for delivery of the parts by gravity to a dispensing position, said dispensing receptacle comprising, a base resting upon a support surface and having a pair of spaced receptacle support elements rising upwardly therefrom, a parts receptacle having a rear wall, a pair of spaced side walls, and an end wall, the end portion of the receptacle opposite the end wall forming a dispensing chute delineated by the side walls and rear wall, the receptacle and chute having an open face opposite the rear wall, said chute being inclined forwardly from the plane of the rear wall toward said open face, a pair of pivot pins projecting outwardly from the receptacle at opposite sides and located on a common axis between the end wall and dispensing chute, bearings on the support elements of the base rotatably journalling said pivot pins and cradling the receptacle for rocking motion upon said base respectively to an upright or inverted position, in upright position said end wall being disposed at the lower end of the receptacle in a horizontal plane to support the container of parts, the axis of said pivot bearings being located above the center of gravity of the receptacle, whereby the weight load forms a partial ballast to balance the receptacle in upright position, the bearings of the support elements being located at an elevation above the support surface less than the space from the outer end of the dispensing chute to the axis of the pivot pins, the axis of the pivot pins providing motion of the end of the chute through an arc substantially greater than 90° upon rocking movement of the receptacle from upright to inverted position, said arc intercepting the plane of the support surface, whereby, in inverted position the receptacle and a parts container are disposed along a downwardly inclined axis with the dispensing chute of the receptacle resting upon the support surface.

7. A dispensing receptacle arranged to reside in upright position to receive a container of parts and to be inverted for delivery of the parts by gravity to a dispensing position, said dispensing receptacle comprising, a receptacle support base, a parts receptacle having an open face, an end wall and a dispensing chute opposite the end wall, a closure plate, pivot means on the receptacle connecting the closure plate to the receptacle, the pivot

means disposed on an axis extending transversely across the chute, the closure plate being movable in an arc from a closed position extending across a portion of said open face and chute to an open position extending at right angles to the plane of said open face, a retainer member pivotally connected to the receptacle and having an end engageable with the closure plate to lock the same in extended open position, a gate mounted upon the closure plate and extending transversely across the dispensing chute when the closure plate is in closed position, the gate having a lower edge delineating an opening, a pair of pivot pins projecting outwardly from the receptacle at opposite sides upon a common axis, bearings mounted on the base rotatably journalling said pivot pins and cradling the receptacle for rocking motion upon said base selectively to an upright or inverted position, in upright position said end wall disposed at the lower end of the receptacle, said closure plate in open position projecting horizontally from the upper end of the receptacle and overbalancing the same, the base having a stop member engaging the bottom of the receptacle, said cross member located at one side of the axis of the pivot bearings below the closure plate to stabilize the overbalanced receptacle in upright position.

25 8. A dispensing receptacle arranged to reside in upright position to receive a container of parts and to be inverted for delivery of the parts by gravity to a dispensing position, said dispensing receptacle comprising, a base, a parts receptacle having a rear wall, a pair of spaced side walls and an open face, the receptacle having an end wall and an outwardly inclined rear wall portion at the opposite end providing a chute, a closure plate extending transversely between the side walls of the receptacle, said closure plate having a portion flush with the open face of the receptacle and having an angular portion projecting inwardly toward the outwardly inclined chute, pivot means adjacent the chute connecting the opposite sides of said angular portion of the closure plate to the side walls of the receptacle and providing pivotal motion of the closure plate to an open position to receive a parts container, a gate mounted upon the inclined portion of the closure plate in a plane generally at right angles to the inclined chute and delineating an opening, releasable latch means pivotally mounted on the receptacle engaging the closure plate in closed position, bearings on said base rotatably journalling said pivot pins, the receptacle being cradled by the pivot pins for rocking motion selectively to an upright or inverted position, in upright position the end wall being disposed at the lower end of the receptacle in a horizontal position to receive a parts container with the closure plate swung to said open position.

55 9. A dispensing receptacle arranged to reside in upright position to receive an open ended container of parts and to be inverted for delivery of the parts by gravity to a dispensing position, said dispensing receptacle comprising, a base having a bottom member resting upon a support surface and a pair of spaced receptacle support elements rising upwardly therefrom, a parts receptacle having a rear wall, a pair of side walls, and an end wall, the end portion of the receptacle opposite said end wall forming a chute delineated by said rear wall and side walls, the receptacle and chute having an open face, said chute being inclined forwardly from the plane of the rear wall toward said open face, a pair of pivot pins projecting outwardly from the side walls of the receptacle and disposed upon a common axis parallel to the rear wall, said axis spaced a lesser distance from the end wall than from the outer end of the chute, the support elements having bearings rotatably journalling the pivot pins, the bearings spaced above the bottom member of the base a greater distance than the space from the receptacle end wall to the axis of the pivot pins, said pivot bearings cradling the receptacle for rocking motion upon the base through an arc of motion substan-

tially greater than 90° selectively to upright or inverted position, in upright position the end wall being disposed at the lower end of the receptacle and spaced above the bottom member of the base to support a container, in inverted position the receptacle being disposed along an inclined axis with the chute disposed at the lower end of the receptacle and engaging the support surface to support the open end of the container.
